(57) **CLAIM**

We claim the ornamental design for a light dimmer, as shown and described.

DESCRIPTION

FIG. 1 is a bottom view of a first embodiment of a light dimmer, showing the new design;

FIG. 2 is a top perspective view thereof;

FIG. 3 is a first side view thereof;

FIG. 4 is a second side view thereof;

FIG. 5 is a third side view thereof;

FIG. 6 is a fourth side view thereof;

FIG. 7 is a top view thereof;

FIG. 8 is another top view of the design of FIG. 1, shown in an alternate state;

FIG. 9 is another top view of the design of FIG. 1, shown in an alternate state;

FIG. 10 is another top view of the design of FIG. 1, shown in an alternate state;

FIG. 11 is another top view of the design of FIG. 1, shown in an alternate state;

FIG. 12 is another top view of the design of FIG. 1, shown in an alternate state;

FIG. 13 is another top view of the design of FIG. 1, shown in an alternate state;

FIG. 14 is another top view of the design of FIG. 1, shown in an alternate state;

FIG. 15 is another top view of the design of FIG. 1, shown in an alternate state;

FIG. 16 is another top view of the design of FIG. 1, shown in an alternate state;

FIG. 17 is another top view of the design of FIG. 1, shown in an alternate state;

FIG. 18 is another top view of the design of FIG. 1, shown in an alternate state;

FIG. 19 is another top view of the design of FIG. 1, shown in an alternate state;

(Continued)

FIG. 20 is another top view of the design of FIG. 1, shown in an alternate state;
 FIG. 21 is a bottom view of a second embodiment of a light dimmer, showing the new design;
 FIG. 22 is a top perspective view thereof;
 FIG. 23 is a first side view thereof;
 FIG. 24 is a second side view thereof;
 FIG. 25 is a third side view thereof;
 FIG. 26 is a fourth side view thereof;
 FIG. 27 is a top view thereof;
 FIG. 28 is another top view of the design of FIG. 22, shown in an alternate state;
 FIG. 29 is another top view of the design of FIG. 22, shown in an alternate state;
 FIG. 30 is another top view of the design of FIG. 22, shown in an alternate state;
 FIG. 31 is another top view of the design of FIG. 22, shown in an alternate state; and,
 FIG. 32 is another top view of the design of FIG. 22, shown in an alternate state.
 The broken lines in the figures illustrate portions of the light dimmer which form no part of the claimed design.
